UNITED STATES PATENT OFFICE.

EARL HURD, OF KANSAS CITY, MISSOURI.

PROCESS OF AND APPARATUS FOR PRODUCING MOVING PICTURES.

1,143,542.

Specification of Letters Patent. Patented June 15, 1915.

Application filed December 19, 1914. Serial No. 878,091.

To all whom it may concern:

Be it known that I, EARL HURD, a citizen of the United States, residing at Kansas City, in the county of Jackson and State of Missouri, have invented certain new and useful Improvements in Processes of and Apparatus for Producing Moving Pictures, of which the following is a specification.

The main purpose of my invention is to provide a method of producing moving picture films from a series of cartoons or drawings photographed in sequence, and which give the effect of moving objects when projected in the usual manner upon a screen. In the drawings which are photographed to produce the successive poses, the objects, which are to be represented as in motion, are drawn in the positions which they are supposed to assume progressively through the series. It is evident that the artist may take certain liberties, drawing upon his imagination in making these drawings in depicting the positions and performances of the persons, animals, inanimate objects or the like, and thereby produce amusing and entertaining effects which are impossible when the photographer must depend upon actual physical moving objects.

One of the objects of my invention is to enable such animated cartoons to be made with the minimum of effort and expense and to facilitate the rapid execution of any series of poses relating to or constituting a single scene. By my process I am enabled to use a single setting or background for an entire scene and to effect the illusion of lifelike movement in successive poses by drawing upon a series of transparent sheets the moving objects arranged progressively according to the sequence of the events which it is desired to depict.

My invention will be understood by reference to the accompanying illustrative drawings in which—

Figure 1, is a front perspective view of an apparatus for carrying out my process; Fig. 2, is an end elevation of the same, showing the front hinged frame swung outwardly and showing also in dotted lines the entire cabinet swung back into horizontal position during the operation of changing the transparent leaf or sheet; Fig. 3, is a vertical section on the line 3—3 of Fig. 1; Fig. 4, is a perspective view of the apparatus shown in Fig. 1, but with the frame carrying a transparent sheet of celluloid or glass car-

rying the motionless portion of the moving object, in position to be clamped to the swinging glass door or frame; Fig. 5 is a front elevation of the celluloid plate and its frame; and Fig. 6 is a fragmentary view of a transparent sheet carrying the moving portion of the movable object.

In my process a single background is used for the entire series of pictures necessary to portray one scene. The background shows all of those portions of the scene that remain stationary and may conveniently be drawn, printed or painted on cardboard or other suitable sheet. I prefer to paint the figures of the background in strong blacks and whites upon a medium dark gray paper and when the transparent sheet carrying the movable objects is placed over this gray tone of the background, the objects on the transparent sheet appear to stand out in relief, giving what may be termed a "poster effect."

The cabinet or supporting case 1, has a hinged door frame 2, carrying a plate of glass 3, and also a frame 6, hinged at 8 to the base 5, of the cabinet and to which the background sheet 10, may be secured.

The transparent sheets of paper 12, upon which the moving or "action" features of the picture are drawn, may be made into book form and secured to the top member of the cabinet as indicated. When a series of pictures or cartoons are to be prepared, the entire book of transparent sheets is first turned back over the top of the cabinet. The background having been prepared and placed in position as indicated in Fig. 1, the bottom sheet of the book, which is now on top, is brought down in front of the background and clamped at the bottom by the clips 14, which are first depressed by means of a lever 15, connected thereto in any suitable manner. The figure which represents the desired movable object may then be drawn in outline by the artist in its proper relation to the background which shows distinctly through the sheet of paper. In Fig. 5, I have indicated the movable object as a woman in the act of spanking a child. Another sheet is then brought over the first sheet in front of the background and held by the clips 14, and upon this is traced those portions of the previously drawn figure which remain in the same position during the next pose and the remaining parts which are in "action" and have moved, are

sketched in or drawn in their desired positions. Thus, in the example illustrated in Fig. 4, only the right arm of the woman and the legs of the child are in action so that these parts only are to be drawn in a different position, the remaining stationary portions being traced.

To further simplify the production of the pictures and reduce the amount of work entailed, I may draw, paint or otherwise place those portions of the movable object which remain stationary during several poses, upon a sheet of transparent celluloid or other transparent medium. It is convenient to mount this transparent celluloid sheet 16, in a frame 17, and detachably secure it in the door frame 2, as by means of pins 18, entering the holes 19, at the inner end and sockets 21 in the other end into which the catches 22 may be turned by means of the thumb knobs 23. With the aid of this device it is only necessary to sketch or draw upon the successive sheets of transparent paper the "action" portions, in the present illustration, the woman's right arm and hand, and the legs of the child, as I have indicated on the sheet 12^a which has been turned upward to show the parts in "action" by themselves. It will be apparent that when sheet 12^a is drawn down in front of the background and the glass door 2, with the attached celluloid sheet 16, is closed against the background, the arm and legs on the sheet 12^a will take the proper position with relation to the stationary portions on the celluloid sheet and the latter will align with the desired part of the background so that the whole will constitute a complete picture having the desired pose. The next succeeding pose will be formed in the same manner, but replacing the sheet of transparent paper with the following sheet and drawing thereon the arm and legs in the position desired to be shown at the next instant. Inasmuch as the background can be seen through a number of sheets, the sheets may be left in position, if desired, until a number have been sketched, the preceding sheets serving as a guide for the artist in drawing the succeeding positions or poses of the moving objects.

After a number of sheets have been sketched, they may be transferred from in front of the background to the rear, occupying the space between the background and the back wall of the cabinet as indicated at 12^b. When the sheets in front of the background have been released from the clips 14, by depressing the lever 15, the background frame 6, may be swung forward, as indicated in dotted lines in Fig. 2, so that said front sheets may be shifted to the rear of the background and the latter may then be swung back into normal position, resting against the stop pin 7. It is

sometimes convenient to hinge the cabinet at 8, to its support so that it may be laid back in the horizontal position during the operation of placing a new sheet in front of the background, as indicated in dotted lines upon the left-hand side of Fig. 2, and the sketching upon the new sheet may be done in this position if desired.

In Fig. 5, I have shown the transparent medium, such as a sheet of transparent celluloid 16, mounted in a frame 17, which may be attached in any suitable manner to the front door frame 2. As previously explained, this transparent sheet 16 is used when there is some portion of the movable object which remains stationary during several poses and upon which is drawn this stationary portion, so that it is only necessary to draw the actual moving parts upon the transparent sheets 12, which change position at each pose. Thus suppose that a boy is to make certain movements with the upper part of his body while the lower part remains in one position; then the lower part will be drawn upon the celluloid sheet 16, as illustrated in Fig. 5, while the upper part will be drawn upon the sheets 12, as shown in Fig. 6, the position upon each succeeding sheet being changed in a manner to give the effect of the "action" when projected upon the screen by the moving picture machine. It will be evident that by employing this sheet 16, carrying the stationary portion of the movable object, much labor is saved and the process of preparing the cartoons for the photogapher is greatly facilitated.

If the movable object has some portion which does not change in form or configuration during the successive poses, and yet does change its relative position upon the background, then I may draw the unchanging portion of the movable object upon a transparent paper or other medium and shift its position with respect to the background at each pose. Thus suppose it is desired to represent a boy running across the picture. His hands, arms and legs would change in posture at each pose but the rest of his body would occupy the same outline or shape in each pose although shifted in position relatively upon the background. In this case I would draw the trunk and head of his body upon a separate transparent sheet independent of the transparent leaves 12, and move said separate sheet to the proper new position at each pose. I would then place a fresh transparent leaf or sheet 12, over the background and covering said separate sheet, tracing the body trunk and head and drawing the arms and legs in the new position joined thereto. If desired, instead of tracing the body, trunk and head, i. e. the unchanging portion of the movable object, each time upon the new sheet, I may leave that part

- blank and place the said separate sheet into the proper position to register with the arms and legs, retaining it in position by means of the clips 14, and the frame of the 5 door 2, while that pose is being photographed. I prefer, however, to trace said portion each time upon the sheet 12, at the same time that the "action" portions are drawn thereon.
- 10 Having described the construction and operation of the separate parts of an apparatus which may be used in carrying out my invention, I will now set forth the steps of the process.
- 15 The background for any scene is first prepared, preferably employing a paper sheet 10, of a medium dark gray color and which may be cardboard, or other non-transparent material, and painting the objects thereon
- 20 in strong blacks and whites. The book of very transparent sheets or leaves 12, having been laid back over the top of the cabinet, the background is tacked or otherwise secured to the hinged support 6. A sheet of
- 25 the transparent paper is brought down in front of the background and held by the clips 14 while the artist sketches, preferably in outline only, the movable objects in their proper relation to the background which
- 30 shows distinctly through the transparent paper. This may be repeated with the proper change in pose of the objects until a number of the transparent sheets are in front of the background, because I prefer
- 35 to use paper which is very transparent and permits the background to be seen through quite a number of sheets. It is also advantageous to have a number of the preceding poses superposed in order that the artist
- 40 may see the effect produced by the successive changes in the positions of the objects. After a certain number of sheets or leaves have been sketched, they are loosened and lifted while the background is swung forward and
- 45 all but one or two of the last sheets are placed in the rear of the background, said last sheet or sheets being again placed in front of the background as it is brought back into normal position to serve as a guide
- 50 for the artist in drawing or sketching the next pose upon the following sheet or leaf which is then brought down from the book 12 and placed under the clips. As previously stated, the cabinet may be turned back
- 55 into horizontal position when the leaves are being turned, if desired. If a movable object or a portion thereof remains in a stationary position during a number of poses, I prefer to draw it upon a transparent cellu-
- 60 loid sheet 16, in its proper relation to the background to thereby avoid the necessity for drawing or tracing this stationary part of the movable object or objects and merely sketching the "action" portions or those
- 65 which change positions at each pose. If

there are certain portions of the movable figures or objects which while occupying different positions in successive poses, yet maintain the same form or configuration, I trace said unchanging portion or portions 70 from the first sheet upon which they are drawn and then move this traced paper to the next position on the background and when the succeeding sheet 12 is brought down in front of the background it also covers the tracing which may then be traced upon the new sheet or leaf, leaving only the "action" parts to be sketched in or added free-hand, thereby facilitating the repetition 75 of the figures.

I have used, in practice, sheets of such transparency that a plurality may be superposed in succession over the background without materially dimming the clearness thereof, so that the picture or scene which is photographed, may be made up of the background and one transparent sheet or a plurality of transparent sheets superposed thereon, each having thereon a part or element of the picture. I believe I am the 80 first to employ a transparent sheet or a plurality of transparent sheets in conjunction with a background which is photographed therethrough upon the negative film.

After the moving or "action" parts have 95 been sketched for all of the poses or positions necessary to portray the entire movement of the scene, the movable parts having been merely sketched in outline by the artist, the figures or objects are then filled in or 100 painted on the reverse side of each of the leaves or sheets in opaque colors, with white, black and gray shades to give the required opacity.

To prepare the negative film, the series of 105 poses are successively photographed with a proper moving picture camera. The ground being in position as indicated in Fig. 1, and the leaves of the book having been all turned back over the top of the cabinet, the first 110 transparent sheet having thereon the movable figures or objects in the first pose, is brought down over the background and fastened by the clips 14 and by the frame of glass door 3, and the first picture is exposed. 115 The effect of the extremely transparent paper is imperceptible over the background, and the movable figures on said transparent paper sheet unite with the background to form a complete picture, the opaque parts 120 of the figures hiding those parts of the background covered thereby. For example, the figure of the woman in Fig. 4, hides that portion of the background beneath her.

After the exposure of the first picture, the 125 cabinet may be turned back into a horizontal position, as indicated in dotted lines in Fig. 2, the door opened, the transparent sheet or leaf loosened from the clips, and placed in the rear of the opaque background as it is

tilted forward. The next leaf or sheet of the book 12 is then brought over in front of the background and fastened in the manner previously described, thereby placing 5 the second pose of the moving picture in readiness to be photographed and so on throughout the entire series.

As previously explained, if the celluloid sheet 16 has been employed as the trans- 10 parent medium to carry a portion of the movable objects which remain stationary during a series of poses, this is attached to the frame of the door at the proper time to be thereby brought into alinement with the 15 background and overlying transparent sheet, coöperating therewith to form the complete picture of the pose.

I have shown the transparent sheets as 20 leaves of a book, but it is evident that said transparent medium may constitute a continuous roll carried by a reel from which the successive sections may be drawn over the background in carrying out the steps of the process constituting my invention.

25 The advantage of using a single background from the entire series of pictures constituting the poses of a scene will be appreciated, especially by those who are familiar with prior methods in which a 30 separate background is used for each pose or picture, even though the main portions thereof may be produced by a duplicating printing process, and moreover a considerable expense is entailed thereby. In my process 35 the work of the artist may be confined to the sketching of those portions of the movable objects which change position with each pose. The work of tracing the unchanging portions of the movable objects, as well as 40 that of painting in the body of the objects within the contour sketched by the artist with opaque colors, may be done by an assistant since it does not require the originality, skill, or ability of the artist. The 45 placing of objects or portions of objects that remain stationary during a number of poses, upon a separate transparent medium, such as a sheet of transparent celluloid, which may be placed successively in alinement 50 with the background and the successive sheets carrying the "action" or changing portions, saves much labor and expense and facilitates the production of the pictures.

55 While I have described in detail the apparatus illustrated in the accompanying drawings and the particular manner of operation, it is to be understood that many changes may be made therein and that the 60 process disclosed herein is not confined thereto. Thus the leaves may be grouped and maintained in the required fixed relation to the background as they are successively brought in front of the background by being in the form of a continuous roll, instead

of being in the form of leaves of a book, and other changes within the purview of my invention will suggest themselves to those familiar with apparatus relating to this art.

I claim—

1. The process of producing moving pictures, which includes the producing on a sheet of suitable material a background containing the parts of a scene which remain stationary during the entire series of 75 pictures embodying the scene, producing on separate sheets of transparent material the movable objects in the successive positions or poses, and photographing said pictures in succession on a cinematograph film, each 80 picture of the series being formed by a separate sheet of said transparent material placed in front of said background sheet, and the background which is visible through said transparent material.

2. The process of producing moving pictures, which includes the producing on a sheet of suitable material a background containing the parts of a scene which remain stationary during the entire series of 95 pictures embodying the scene, producing on separate sheets of transparent material those portions of the movable objects which occupy different positions in successive pictures, producing upon an independent transparent medium those portions of the movable objects which remain stationary during a number of successive pictures, and superposing said medium in the same position upon the background simultaneously 100 with the successive sheets of transparent material, the parts on the latter uniting with those on said medium to form with the visible background the complete pictures in each position or pose.

3. The process of producing moving pictures, which includes the producing on a sheet of suitable material the background of a scene, producing upon separate sheets of transparent material the movable objects in successive positions, arranging said sheets in a group fixed in definite relation to the background and separately placing the sheets successively in front of the fixed background, whereby they will be held in 115 the same position with respect thereto.

4. The process of producing moving pictures, which includes the producing upon a transparent medium that portion of the movable object which remains in the same position during successive pictures or poses, producing upon separate sheets of transparent material the remaining portions of the movable object in successive positions, and superposing said transparent medium 120 successively upon said sheets so that the corresponding parts shall be in registry to 125 form the complete object.

5. The step in the method of producing moving pictures, which includes producing 130

70

85

upon a transparent medium to be used in conjunction with a background only those parts of the movable objects of the picture which remain in unchanged position during

5 a series of successive positions or poses.

6. An article of manufacture for the production of moving pictures, comprising a series of transparent leaves or sheets secured at one edge in book form and having thereon the representations of those portions of the movable objects which change in successive pictures or poses.

7. An article of manufacture for the production of moving pictures, comprising a 5 transparent sheet or plate having sufficient rigidity to maintain its shape in all positions, and having thereon the representations of those portions of the movable objects which remain in the same position in

20 successive pictures or poses.

8. The process of producing moving pictures, which includes the producing upon a suitable material a background comprising

the parts of the picture which remain stationary during successive poses of the movable parts of the picture, producing upon sheets of transparent material the movable objects which appear in the successive positions or poses, superposing said transparent sheets successively upon said background to bring the movable parts into the desired relation therewith, and photographing said pictures in succession on a cinematograph film, each picture of the series being formed by the parts appearing on a plurality of said transparent sheet in conjunction with the background, the latter showing clearly through the transparent sheets superposed thereon.
